UNITED STATES PATENT OFFICE.

GEORGE C. McAULEY, OF DETROIT, MICHIGAN.

SHOE ATTACHMENT.

Application filed July 10, 1923, Serial No. 650,625. Renewed September 10, 1925.

To all whom it may concern:

Be it known that I, GEORGE C. McAULEY, a citizen of the United States, residing at Detroit, in the county of Wayne and State of Michigan, have invented certain new and useful Improvements in Shoe Attachments, of which the following is a specification.

In carrying out the present invention, it is my purpose to provide an attachment for 10 shoes to be used by bowlers, which will co-operate with the ordinary shoe for answering all of the purposes attributed to the conventional types of bowlers' shoes that are now universally used.

15 The primary object of this invention is the provision of such an attachment that may be readily applied or removed from the ordinary shoes in a simple and expeditious manner for preventing the slipping of the 20 bowlers while playing the game and for protecting the shoe from wearing.

A still further object is to provide such a shoe attachment that may be carried in small compass, such as in the pockets of the 25 bowlers, and one that may be manufactured and marketed at relatively small cost.

Yet another object is to provide such an 30 attachment for shoes that may be employed in conjunction with ordinary types of shoes for answering all of the purposes now attributed to bowling shoes that may be readily adjusted to widely varying sizes of shoes.

Additional objects will be apparent as the 35 nature of the invention is better understood, and the following detailed description is read in connection with the accompanying drawing, wherein:

The figure is a perspective of my improved shoe attachment.

40 Now, having particular reference to the drawings my novel attachment for shoes embodies a strip 5, preferably of buckskin, cut to the configuration of the sole of an ordinary shoe. The side and front edges of this strip of material are slit inwardly at spaced points thereon, for providing tabs 6 that are usually turned and positioned in overlapping relation with each other for providing a skirt portion around the sides and front edges of this strip for engagement

with the side and front edges of the usual shoe sole.

Each of the tabs 6 so formed is provided with a central eyelet 7 and interlaced through these eyelets is a desirable form of 55 lacing 8 that may be drawn up or loosened for increasing or diminishing the overlapped relation of the tabs with each other for thereby actuating the strip to varying size 60 shoe soles.

Riveted at 9 to one end of the upstanding portion of the strip 5 formed by the tabs 6 is one end of a strip 10, while similarly secured to the opposite end of said upstanding portion is a short strap 11 that carries 65 at its free end a buckle 12, through which is adapted to be positioned the free end of the strap 10, that is formed with a desirable number of openings for selectively receiving the usual pivoted tongue of the buckle. 70

It will be of course apparent from the foregoing, that the strip 5 is to be positioned upon the sole of the shoe, and that the strip 10 is to be engaged around the heel portion 75 thereof and connected to the short strap 11 through the medium of the buckle 12 for thereby effectively regulating said strap 5 upon the sole of the shoe.

Numerous advantages of a shoe of this character will be at once appreciated by 80 those skilled in the art, and even though I have herein shown and described the most preferred embodiment of the invention with which I am at present familiar, it is nevertheless to be understood that minor changes 85 may be made therein, without departing from the spirit and scope of the invention as claimed.

Having thus described my invention, what I claim as new, and desire to secure by Letters-Patent, is:

A shoe attachment comprising a strip of material adapted to be applied to the sole of a shoe, and when applied having its rear edge spaced from the heel of the shoe, the 95 said strip being provided with a marginal portion adapted to be folded up around the edge of the sole of the shoe, said marginal portion being provided with slits forming tongues, which may overlap each other, each 100

tongue having an opening, a securing strap attached to the marginal portion of the strip and at the rear edge of the strip and at the openings in the terminal tongues and adapted to extend around the back of the shoe upper and lacing passing through the openings of all of the tongues of the marginal

portion of the strip and serving as means for drawing the tongues in overlapped close proximity with the upper of the shoe and 10 the strap in close proximity with the rear portion of the upper of the shoe.

In testimony whereof I affix my signature.
GEORGE C. McAULEY.
